UNITED STATES PATENT OFFICE.

ERNEST LAMORT AND MARCEL LAMORT, OF VITRY-LE-FRANCOIS, FRANCE.

SUCTION BOX FOR THE MANUFACTURE OF PAPER AND SIMILAR PRODUCTS.

Application filed March 15, 1921. Serial No. 452,530.

(GRANTED UNDER THE PROVISIONS OF THE ACT OF MARCH 3, 1921, 41 STAT. L., 1313.)

To all whom it may concern:

Be it known that we, ERNEST LAMORT and MARCEL LAMORT, citizens of Luxemburg, residing at Vitry-le-Francois, Marne, France, 5 have invented new and useful Improvements in and Relating to Suction Boxes for the Manufacture of Paper and Similar Products (for which we have filed an application in France Jan. 2, 1920, Patent No. 508,109), of 10 which the following is a specification.

This invention relates to a type of suction boxes with rolling active surfaces and without any slide valves, which boxes are to be used in the manufacture of paper and similar products. The arrangement in question 15 has these advantages upon the types previously known and hitherto used that they effect a saving of metallic cloth and power, whilst the quality of the products which are 20 manufactured is improved.

It will be useful to remind here that the various types of suction boxes as have hitherto been used in machines for making paper or cardboard are divided into two classes, 25 namely;—

Fixed boxes to which a longitudinal alternating movement is sometimes imparted and 30 Rotary boxes acting at the same time as "presses coucheuses"; the latter system has been proposed with a view to allowing in the case of paper machinery working at a high linear speed of the sheet, of reducing the considerable wear of the metallic cloth due to the friction of the said metallic cloth on 35 the suction surfaces of the fixed boxes, whilst reducing at the same time the power absorbed by the friction. However, if the said rotary boxes are capable of reducing in a certain degree the wear of the metallic cloth, they do not save power at all. Indeed, 40 the said boxes are situated at the end of the metallic cloth, they act upon a sheet of paper which is already too much formed and along a surface which is too much reduced, therefore 45 the said boxes work with an excessive amount of suction, and require a corresponding power for the production of the vacuum, moreover, they are very expensive.

The apparatus according to the present 50 invention allows of doing away at the same time with the friction surface of the fixed

boxes and with the slide valves which are necessary owing to the variation of the sizes which are manufactured on the paper machines.

55

In the accompanying drawings which illustrate the invention by way of example.

Figure 1 is a sectional elevation along the line 1—1 of Fig. 2 of a machine constructed according to the present invention.

60

Fig. 2 a front elevational view of the same machine,

Fig. 3 is a plan view of the machine,

Fig. 4 is a detail showing one mode of construction of the joint made at the end of 65 a roller of the machine,

Fig. 5 is a detail showing a modification of construction of the said joint,

Figs. 6, 7 and 8 are respectively an elevation, plan, and a lateral elevation of an arrangement designed to replace the slide valves which are generally used in paper machinery,

70

Fig. 9 is an elevation of the modification of construction of the said arrangement.

75

Referring to Figs. 1, 2 and 3 it will be seen that according to the present invention the machine comprises three horizontal and parallel rollers 1, 2 and 3 arranged so as to leave between them a certain space 4 constituting the suction chamber or box. The axes of the rollers 1 and 2 are situated in one and the same horizontal plan and the said rollers are on one side tangent to the roller 3, and on the other side to the metallic cloth 80 5 along their upper generating lines *a*—*b* and *c*—*d* respectively; the active surface of suction is therefore limited by the rectangle *a*—*b*, *c*—*d*, the distance between the two generating lines *a*—*b* and *c*—*d* is variable 85 but it may be mentioned by way of example that in the case where the diameter of the rollers 1 and 2 is 200 mm. the said distance is about 250 mm.

85

The rollers 1, 2 and 3 are mounted in the usual manner. The rollers 1 and 2 are provided with a brass jacket and the roller 3 is also provided with a brass jacket which is covered with rubber or other similar material. The axes of the rollers are mounted 100 on ball bearings arranged on the lateral flanges 6 and 7 supported by the longitudi-

nal of the table of manufacture, or by means of suitable supports.

The roller 3 is actuated by means of a pulley, the said actuation being effected in such a manner that the peripheric speed of the rollers 1 and 2 shall correspond exactly to the linear speed of the metallic cloth 5 with which they are in contact along the generating line $a-b$ and $c-d$ mentioned above.

10 In view of the fact that the surface of the roller 3 has, as said above, a rubber covering, a tight-joint fit is obtained between the rollers 1 and 3 on one side and the rollers 2 and 3 on the other side. Moreover, the 15 said rubber covering allows of ensuring the carrying over of the rollers 1 and 3 with a speed corresponding exactly to that of the metallic cloth as said above, thus suppressing the friction of the cloth on the rollers.

20 The lateral tightjoint fit at each end of the said rollers is effected by means of a hydraulic joint and Figs. 4 and 5 of the accompanying drawing illustrate two modifications of construction of the said joint.

25 The rollers, which are constructed in the same manner as rollers ordinarily used in the paper machinery, are provided at the ends of the tubes which constitute them, with a metallic ring 8 (Fig. 4) fixed on the 30 inside and provided with a small circular groove 9 along the whole periphery of the said ring which rotates with the corresponding roller. A fixed socket 10 engages in the said ring and carries at one end another 35 ring 11 arranged exactly opposite the ring 8; at its other end the socket 10 engages with a boss 12 which is secured to the corresponding Figure 6 or 7, or is cast in one with the said flange; a certain play 13 has 40 been left between the end of the socket 10 and the end of the boss 12 in such a manner as to allow of adjusting the pressure between the two rings 8 and 11.

45 The socket 10 and the boss 13 are provided on their periphery with a rubber band 14 rigidly secured by means of hoops 15 and 16. The tension of the band 14 is adjusted in such a manner as to press the ring 11 against the ring 8 with a sufficient pressure. 50 In order to ensure an air-tight-joint between the two said rings a water circulation has been provided which can be ensured either by the moisture of the sheet of paper itself; or by means of a water inlet through a suitable conduit such as 17 and a small channel 55 18 provided in the socket 10.

60 In the example illustrated in Fig. 5 of the drawings the hydraulic joint above mentioned consists of a double groove 9', 9'' formed on two of the faces of the ring 8 which is integral with the tube of the roller at the end of the latter. In this mode of construction the socket 10 is pressed in a suitable manner against the end 19 of the tube 65 20 of the corresponding rollers by means of

a spiral spring 21 arranged between the ends of the socket 10 and bosses 12 which are situated opposite to each other and is lodged below the rubber band 14 above mentioned. In this case the band 14 does not act any longer as a spring as in the case of Fig. 4, but serves only for ensuring a tightjoint fit.

It should be pointed out that the two examples of hydraulic joint indicated in 75 Figs. 4 and 5 of the drawing and described above are only given by way of example and do not limit at all the invention and that they may be combined and constructed in any other suitable manner so as to ensure 80 the same result being obtained, that is for establishing under the sheet of paper or more exactly under the metallic cloth that supports it, a certain space 4 isolated from the free air; the said space being limited by 85 the contact generating lines $a-b$ and $c-d$ of the rollers 1 and 2 with the cloth 5 on one side and the contact generating lines of the rollers 1 and 2 with the roller 3 on the other side, and constituting the suction box. 90

As to the production of vacuum in the box 4 use is made for this purpose of the known means which are applied in the systems of suction boxes (syphon, injector, suction pump, etc.). To this end, the flanges 95 6 and 7 are provided with nozzles communicating with the chamber 4; in the details of which it is not necessary to enter here. It should be pointed out that thanks to the ball bearings mounted on the flanges 6 and 7 and thanks to the lubrication which is constantly ensured by the water of the hydraulic joints, any resistance due to the friction is suppressed, thereby obtaining the second 100 of the industrial results mentioned at the 105 beginning of the description.

When the machine is intended for the manufacture of papers having constantly the same size such as, for instance, the papers to be used in rotary presses for printing 110 newspapers the suction box above described works on its whole length between the flanges 6 and 7, the spacing apart of which corresponds to the greatest width of the paper which is manufactured on the machine. 115

When, on the contrary, the question is of machinery intended for the manufacture of papers having variable sizes, the arrangement according to the present invention 120 comprises a particular device replacing the various slide valves which have hitherto been used in this kind of manufacture.

Figs. 6, 7 and 8 of the accompanying drawings on one side and Fig. 9 on the other side show two modes of construction of the 125 said device.

Referring to Figs. 6, 7 and 8, it is seen that in the present case, the boxes previously described for constant sizes, comprise on the 130

outside of the flanges 6 and 7, two tables 22 and 23 arranged horizontally in such a manner as to correspond exactly with the upper generating lines $a-b$ and $c-d$ of the 5 rollers 1 and 2 of the box.

In the example illustrated in the drawing, a machine with three boxes has been illustrated allowing of obtaining a certain maximum size (two meters for instance) and a 10 certain minimum size (1M.40 for instance). In this case it is possible to reduce the active width of the boxes by about 0M.30 at each end. The width l^1 of the metallic cloth is then about 2M.20 cm.

15 The group of three boxes above-mentioned and illustrated in the accompanying drawings, is combined with two continuous rubber bands 24, 25 which are wound up on two drums 26, 27 for the bands 24 and 28, 20 29 for the bands 25, the said drums being capable of a lateral adjustment whilst remaining in a perfect alignment. This alignment is obtained in an identical manner to that of the pulleys carrying the belt-guides 25 of the tables of manufacture; consequently it is not necessary to insist here on that point.

The said drums are provided with small lateral flanges 26', 27', 28', 29', intended to 30 ensure with certainty the guiding of the above-mentioned rubber bands.

In order to facilitate the reading of the drawings, the two drums 26 and 27 that lead the band 24 have been illustrated in the 35 position which they occupy when the machine works for producing sheets of the maximum size, that is in the latter case the said band does not intervene.

On the contrary the two drums 28 and 29 40 which lead the band 25 have been illustrated in the position which they occupy when the machine works for producing sheets of the minimum size, that is in the latter case the said band works on its entire width. Of 45 course the two members above mentioned may occupy all intermediate positions between the previous ones according to conditions required by the various sizes, which it is necessary to manufacture.

50 In any case the bands 24 and 25 ensure in this manner the closing of the boxes by being applied by the atmospheric pressure on the upper generating lines of the rollers that support directly the metallic cloth and 55 the inside edges of the said bands which form joints with the edges of the sheet of paper, the said edges corresponding with the inside edges of the belt-guides.

As shown in the drawing, the arrangement 60 comprises also an intermediate drum 30 which acts as a guide and support for the band 24 and an intermediate drum 31 the object of which relatively to the band 25 is the same as the former drum.

65 In the mode of construction illustrated

in Fig. 9 of the drawing, it has been supposed that the three boxes were coupled which allows a simpler construction.

Indeed; in the latter case, for a number n of boxes it will be enough to establish two flanges and two bands, then instead of $3 \times n$ rollers, it will be enough to have $2n+1$ rollers. It will be seen that under these circumstances for a machine comprising a group of five boxes, which number is considered as a maximum, it will be enough to establish 11 rollers instead of 15.

70 The arrangement which has been described above has also for its result to take a minimum of space on the table of manufacture which constitute an advantage from several practical points of view, whilst maintaining an absolute independence of each box, the particular degree of vacuum of each 75 independent box may be adjusted as in the case when use is made of independent boxes.

80 On the other side the arrangement indicated in Figs. 6, 7 and 8 of the drawing allows of suppressing the slide valves.

85 Referring to the latter figures, it will be seen that additional boxes 32, 33 constructed like the previous ones, but having similar length have been added to the group of main boxes which has been previously described. The arrangement of the said additional boxes is that indicated on the drawing (Figs. 6 and 7) the direction of advancement of the cloth being supposed to be that of the arrow f ; they are therefore placed 90 after the group of main boxes g^1, g^2, g^3 . Moreover, they may be displaced transversely for the whole width of the paper machine in the direction of the arrows $x^1, 95 y^1, x^2, y^2$.

100 In order to allow the said transverse displacement taking place, the flanges of the said additional boxes are capable of sliding in suitable sliding members and the said boxes are arranged in such a manner that 105 they will cross each other, if necessary. Moreover, the sliding members of the said boxes are prolonged in such a manner as to allow the latter of sliding through an amount which is sufficient for bringing them 110 opposite the tables 22 and 23.

115 When manufacturing certain products, the said additional boxes complete the action of the group of the main boxes in the position chosen for the entire width of the cloth according to the results which it is desired to obtain. Here especially, it is possible to combine the action of the said boxes with those of the main boxes in the following manner:

120 There is only a length 12 between the supporting flanges 6 and 7 of the main boxes which length corresponds to the minimum size and this has for result that the additional boxes extend them for the suction for 125 130

all widths of sheets comprised between the maximum size $\frac{7}{8}$ and the minimum $\frac{7}{16}$. In this case, of course, the group of the main boxes is no longer provided with the bands 5 24 and 25 which have thus become unnecessary.

Lastly, the sliding boxes above mentioned may be made of any suitable length which enables them to act as main boxes in the case 10 of variable sizes. In order to obtain the said result it is enough that the outside flanges shall correspond to the edges of the sheet of paper which is manufactured.

Having now particularly described and 15 ascertained the nature of our said invention and in what manner the same is to be performed, we declare that what we claim is:—

1. A suction-box for paper-making machines, comprising fixed end supports, a 20 pair of upper rollers journaled in said end supports and each tangent at its upper surface with the metallic cloth of the machine, a third roller journaled in said end supports and arranged beneath and in contact with 25 said upper rollers so as to provide a suction space between said rollers, said end supports and the metallic cloth, the lower roller having its surface covered with rubber and adapted to drive the upper rollers at a 30 peripheral speed equal to the linear speed of the metallic cloth, and a hydraulic joint between each end of each roller and its end support.

2. A suction-box as set forth in claim 1, 35 wherein the hydraulic joint at each end of each roller comprises a ring on the inner cylindrical surface of the roller, a fixed boss, a socket supported on said boss with provision for endwise play, a ring carried 40 by said socket and arranged within the end of the roller with its outer edge face in en-

gagement with the inner edge face of the ring carried by the roller, said coacting edge faces having corresponding coacting circular grooves therein, and a rubber band secured 45 to the boss and socket and exerting its tension to maintain a tight contact between said rings.

3. A suction-box as set forth in claim 1, including means adapting said suction-box 50 to the manufacture of different widths of paper, said means comprising two sets of aligned drums at the opposite ends of the suction-box supporting two parallel endless bands at right angles to the longitudinal 55 axes of the rollers, said sets of drums together with said bands being adjustable toward and away from each other, said bands being arranged above said rollers so that their lower runs are adapted to make 60 contact due to atmospheric pressure with the upper surfaces of the two upper rollers with the inside edges of the bands forming a joint with the edges of the sheet of paper, thereby insuring the closing of the suction 65 space.

4. The combination with a main suction-box of a given length, of an auxiliary suction-box arranged in cooperative relation to 70 said main suction-box, said auxiliary suction-box being longitudinally slidable in a direction parallel to the longitudinal axis of the main suction-box.

In testimony whereof we have signed our name to this specification in the presence of 75 two subscribing witnesses.
